(57) **CLAIM**

The ornamental design for an electrical plug device, substantially as shown and described.

DESCRIPTION

FIGS. 1-7 are views of the electrical plug device with its conductive blades in an extended position.

FIG. 1 is a front perspective view of the electrical plug device, FIG. 2 is a front view of the electrical plug device,

FIG. 3 is a back view of the electrical plug device,

FIG. 4 is a right side view of the electrical plug device,

FIG. 5 is a left side view of the electrical plug device,

FIG. 6 is a top view of the electrical plug device, and

FIG. 7 is a bottom view of the electrical plug device.

FIGS. 8-14 are views of the electrical plug device with its conductive blades in a retracted position.

FIG. 8 is a front perspective view of the electrical plug device, FIG. 9 is a front view of the electrical plug,

FIG. 10 is a back view of the electrical plug device,

FIG. 11 is a right side view of the electrical plug device,

FIG. 12 is a left side view of the electrical plug device,

FIG. 13 is a top view of the electrical plug device; and,

FIG. 14 is a bottom view of the electrical plug device.

The portions of the electrical plug device shown in broken lines form no part of the claimed design.
